UNITED STATES PATENT OFFICE

KARL MAIER, OF STUTTGART, GERMANY, ASSIGNOR TO UNION SPECIAL MASCHINEN-FABRIK, G. M. B. H., OF STUTTGART, GERMANY

APPARATUS FOR PRODUCING STITCHED TRIMMING STRIPS

Application filed October 18, 1926, Serial No. 142,377, and in Germany November 12, 1925.

The invention relates to new and useful improvements in an apparatus for producing stitched trimming strips, and more particularly a trimming strip wherein a cord is enclosed within a narrow strip and secured therein by a line of stitching.

An object of the invention is to provide an apparatus wherein a folding guide is used for infolding the edge portions of a narrow strip, and for folding said edge portions about a cord or cords, after which the thus folded narrow strip is passed through a former so that the parts are formed into the desired finished condition for the trimming strip, and while so held by the former, are fed to a stitching mechanism located immediately in rear of the former so that the parts may be secured together.

A further object of the invention is to provide an apparatus of the above character with a feeding mechanism which includes an upper feed dog engaging a trimming strip directly in rear of the needles, and wherein said upper feed dog is shaped on the under face thereof to conform to the upper surface of the finished trimming strip.

These and other objects will in part be obvious and will in part be hereinafter more fully disclosed.

In the accompanying drawings which show one embodiment of the apparatus—

Figure 1 is a perspective view of a portion of a sewing machine, and with the necessary apparatus attached to the same for carrying out the invention;

Fig. 2 is a plan view of a portion of the parts shown in Fig. 1;

Fig. 3 is a sectional view on the line A—B of Figures 2 and 6;

Fig. 4 is a sectional view on the line C—D of Figures 2 and 6;

Fig. 5 is a plan view of the former and the end of the guide associated therewith;

Fig. 6 is a bottom plan view of the former;

Fig. 7 is a perspective view of a trimming strip made in accordance with the invention, said section being taken on the line E—F of Fig. 2, and

Fig. 8 is a sectional view of the end of the upper feed dog, on the line G—H of Fig. 2.

Before describing the apparatus, a brief description will be given of a trimming strip made in accordance with the present invention. This trimming strip includes two cords 1, 1 and a narrow strip 2. The ribbon strip is infolded adjacent the sides thereof, and these infolded portions are respectively folded about the cords. The edge of the strip carried around the cord extends well underneath the folded in portion so that the line of stitching may pass through the parts parallel with the cord, and said line of stitching will penetrate the infolded portion of the ribbon strip, the edge portion thereof folded underneath the infolded portion, and the body of the narrow strip. There is, of course, a line of stitching adjacent each cord. This trimming strip may be modified, and a single cord alone may be used, but the above trimming strip is illustrated and described for the purpose of making clear the invention.

The apparatus embodying the invention consists of a sewing machine to which is attached a folder guide and a former. The folder guide is illustrated at 5 in the drawings, while the former is indicated at 9. The narrow strip 2 is first guided through a sponge cup 3, where the ribbon strip comes in contact with the sponge and is saturated with oil. The narrow strip next passes through a guide 4 which leads the strip into the folder 5. This folder 5 consists of two tubular members 5, 5, and a guide plate 6, so that the narrow strip as it passes through the folder will be folded at the side portions thereof into tubular shape. At the same time, the two cords 1, 1 are introduced through guides 1^a, 1^a, respectively so that the side portions 8 of the narrow strip are folded about the cords 1, 1, respectively. That is to say, the narrow strip is infolded, and the infolded portions are folded around and beneath the cords as described more in detail above in connection with the trimming strip. This is all accomplished by the folder. The folder is secured to the bed plate of the machine in the usual manner, and is located in front of the needles, which are indicated at 7, 7. The folder is provided with an extension 10, and secured to said extension and cooperating therewith.

is the former 9. This former 9 at the inner side thereof is shaped so as to represent two large arcuate inverted grooves 11 which receive the two curls or infolded portions of the narrow strip from the folder 5. These 5 large grooves 11 are tapered or narrowed down to relatively smaller arcuate grooves 12 and into side grooves 13. The tubular parts of the strip issuing from the folder and passing into the former 9 are pressed or shaped into the rounded ribs 14 with the cords 1 inserted therein, and into the flat parts 15 as shown in Fig. 7 of the drawings. The delivery end of the former is shaped to 10 conform precisely to the desired shaping of the trimming strip. As clearly shown in Fig. 2 of the drawings, the former is located directly and closely in front of the needles 7, 7, and these needles are so positioned as to form 15 lines of stitching which pass through the pressed flat parts 15 adjacent the cords 1, 1. These lines of stitching secure the parts together, and hold the parts of the strip encircling the cords close together, and yet so that they may be raised slightly, if desired. 20 It will be noted that the sewing machine has no presser foot. The former takes the place of the presser foot. The folder 5 is provided with an extension 10, and the former is secured to this extension by the screws 25 9^a, 9^b. One side of the delivery end of the former is shortened so that the needles 7, 7 which are set in a line diagonally of the line of feed, may be brought close to the end of 30 the former.

35 Directly in rear of the needles is a feed dog 17. This is of the usual construction of the upper feed dog so far as mounting and operation of the same is concerned. The end of 40 the feed dog, however, is shaped so as to extend close up to both needles, and the under face of the feed dog is shaped similar to the shaping of the upper under face of the former 9 which bears on the trimming strip.

45 It is obvious that minor changes in the details of construction and the arrangement of the parts may be made without departing from the spirit of the invention as set forth in the appended claims.

50 Having thus described the invention, what I claim as new and desire to secure by Letters Patent, is—

1. The combination of a folder, a guide for directing a narrow strip into said folder, said folder being shaped so as to roll in the edge portions of the narrow strip and turn the edges of the infolded portions underneath said 55 respective infolded portions, cord guides for directing cords into said inturned edge portions of the narrow strip, a former located at the delivery end of the folder and having a tapered passage therethrough shaped so as to press the inturned edge portions of the narrow strip flat against the body portion 60 of the narrow strip adjacent the cords, and

stitching needles located at the delivery end of the former for stitching through the parts and securing the same together.

2. The combination of a folder, a guide for directing a narrow strip into said folder, said folder being shaped so as to roll in the edge portions of the narrow strip and turn the edges of the infolded portions underneath said respective infolded portions, cord guides for directing cords into said inturned edge portions of the narrow strip, a former located at the delivery end of the folder and having a tapered passage therethrough shaped so as to press the inturned edge portions of the strip flat against the body portion of the narrow strip adjacent the cords, stitching needles located at the delivery end of the former for stitching through the parts and securing the same together, and a feed dog engaging the narrow strip on the upper face thereof after it is stitched for drawing the narrow strip through the former.

3. The combination of a folder, a guide for directing a narrow strip into said folder, said folder being shaped so as to roll in the edge portions of the narrow strip and turn the edges of the infolded portions underneath said respective infolded portions, cord guides for directing cords into said inturned edge portions of the narrow strip, a former located at the delivery end of the folder and having a tapered passage therethrough shaped so as to press the inturned edge portions of the narrow strip flat against the body portion of the narrow strip adjacent the cords, stitching needles located at the delivery end of the former for stitching through the parts and securing the same together, and a feed dog engaging the narrow strip on the upper face thereof after it is stitched for drawing the narrow strip through the former.

4. In a sewing machine, the combination of a work support, a folder attached to said work support for guiding and infolding the edge portions of a narrow strip, means for guiding cords into the folded portions of the narrow strip, a former located at the delivery end of the folder, said former having a tapered passageway therethrough conforming in cross section to the shape of the desired finished article whereby the infolded narrow strip passing from the folder through the former will be given its desired final shape, stitching needles located at the delivery end of the former and close thereto for stitching the infolded parts of the narrow strip, and an upper feed dog directly in rear of the needles for engaging the narrow strip and pulling said narrow strip through said folder and former.

5. In a sewing machine, the combination of a work support, a folder attached to said

work support for guiding and infolding the edge portions of a narrow strip, means for guiding cords into the folded portions of the narrow strip, a former located at the delivery end of the folder, said former having a tapered passageway therethrough conforming in cross section to the shape of the desired finished article whereby the infolded narrow strip passing from the folder through the former will be given its desired final shape, stitching needles located at the delivery end of the former and close thereto for stitching the infolded parts of the narrow strip, and an upper feed dog directly in rear of the needles for engaging the narrow strip and pulling said narrow strip through said folder and former, said feed dog having the under face thereof shaped so as to conform to the upper face of the article being stitched.

6. In a sewing machine, the combination of a work support, a folder attached to said work support for guiding and infolding the edge portions of a narrow strip, means for guiding cords into the folded portions of the narrow strip, a former located at the delivery end of the folder, said former having a tapered passageway therethrough conforming in cross section to the shape of the desired finished article whereby the infolded narrow strip passing from the folder through the former will be given its desired final shape, stitching needles located at the delivery end of the former and close thereto for stitching the infolded parts of the narrow strip, an upper feed dog directly in rear of the needles for engaging the narrow strip and pulling said narrow strip through said folder and former, said feed dog having the under face thereof shaped so as to conform to the upper face of the article being stitched, and means for moistening the outer face of the narrow strip with oil as it passes into the folder to aid in the free passage of the narrow strip through the former.

7. The combination of a folder for inter-folding fabric parts, an independent tapered former at the delivery end of the folder for receiving said interfolded parts and for crowding said interfolded parts into close contact with each other, a feeding mechanism including a feed dog for engaging the upper face of the interfolded fabric parts at a point in rear of the former for drawing the interfolded fabric parts through the former, and a stitching mechanism including needles adapted to pass though the interfolded parts of the fabric between the former and the feed dog for securing said interfolded parts.

In testimony whereof, I affix my signature.
KARL MAIER.
